LIGHTING FIXTURE

Joseph M. Feldman and Rolando S. Vasquez, Los Angeles,
Calif., assignors to The Feldman Company, Los
Angeles, Calif.

Filed Nov. 29, 1972, Ser. No. 310,335

Term of patent 14 years

Int. Cl. D26—05; D11—05

U.S. Cl. D48—3

FIG. 1

FIG. 4

FIG. 5.

FIG. 6.

FIG. 7.

FIG. 1 is an isometric view, as viewed from the side, of a lighting fixture showing our new design;

FIG. 2 is a bottom isometric view thereof;

FIG. 3 is a top plan view thereof;

FIG. 4 is a bottom plan view thereof on a reduced scale;

FIG. 5 is a bottom isometric view of a second embodiment of our new design;

FIG. 6 is a top plan view thereof; and

FIG. 7 is a greatly enlarged fragmentary sectional view of the globe common to both embodiments.

We claim:

The ornamental design for a lighting fixture, substantially as shown and described.
